CATHEAD CONSTRUCTION

Daniel L. Butler, Rodessa, La.

Application March 28, 1938, Serial No. 198,382

1 Claim. (Cl. 242—117)

This invention relates to a cathead construction such as used on drawworks, or hoists. It is the present practice to secure catheads to the shafts by means of a tight tapered key. From time to time the catheads must be removed for repairs, or when they are worn out, and considerable difficulty is occasioned in removing them from their shafts. One of the reasons for this difficulty is that there is very little space between the inner end of the cathead and the adjacent end of the cathead frame.

The general object of this invention is to provide a cathead construction which will overcome this difficulty, and which will provide a simple construction enabling the worn part of the cathead to be readily removed when necessary.

In accordance with the invention, the cathead involves the use of an outer spool, or shell, which has a loose driving connection to the cathead body to enable the cathead body to rotate it. This spool, or sleeve, has the usual enlarged heads at its ends to retain the line, and is, of course, subjected to considerable wear due to the abrading effect of the line running off and on to the cathead. Usually the wear at the inner head will be considerably greater than at the outer head, due to the fact that the line from a cathead generally runs in toward the axis of the well. With an ordinary cathead construction this wear necessitates repair work to be done on the cathead from time to time. One of the objects of this invention is to provide a construction whereby the cathead spool can be readily removed and applied in a reverse position so as to bring the wear on the other end of the spool. In this way the life of the cathead without requiring repair, can be substantially doubled.

On account of the wear of the cathead spool, it would be advantageous to have the spool of very hard wear-resisting material, but as catheads are usually made in one piece, this would result in a cathead of considerable expense, as the entire piece would necessarily be made of the wear-resistant material. My invention is advantageous in this regard, because it enables a spool carrying a relatively small amount of material but of a hard and wear-resistant material to be employed on a cathead body of ordinary relatively inexpensive steel or wrought iron.

Further objects of the invention will appear hereinafter.

The invention consists in the novel parts and combination of parts to be described hereinafter, all of which contribute to produce an efficient cathead construction.

A preferred embodiment of the invention is described in the following specification, while the broad scope of the invention is pointed out in the appended claims.

In the drawing

Fig. 1 is a vertical section through a cathead embodying my invention, and showing an adjacent portion of the jack shaft to which it is attached. In this view the adjacent end face of the drawworks frame is indicated, and the end of the shaft is shown partially in section, to illustrate its connection to the cathead body.

Fig. 2 is a cross-section taken on the line 2—2 of Fig. 1, and further illustrating the rigid driving connection between the shaft and the hub 10

15 of the cathead body.

Fig. 3 is a cross-section taken about on the line 3—3 of Fig. 1, and illustrating the loose key connection between the spool and the neck of the cathead.

In practicing the invention, I provide a cathead body 1, which is made of ordinary steel, and provided with an integral hub 2 at one end. This body 1 preferably extends considerably beyond the end of the jack shaft 3 to which the cathead 25 is attached. The cathead body is attached to the jack shaft with the usual type of tapered key 4 driven into aligning key seats or slots 5 in the hub, and in the shaft.

The inner end of the hub 2 is located quite 30 close to the end face of the frame of the drawworks, which supports the jack shaft 3, and the position of this end face is indicated by the line 6 in Fig. 1. The projecting portion of the cathead body 1 is formed with a neck 7 of reduced 35 diameter, and on this neck I provide a spool 8 in the form of a sleeve with slightly enlarged heads 9 at its ends. The inner face of this spool and the outer face of the neck 7 have grooves 10 cut therein to receive a straight key 11; that is 40 to say, a key that is untapered and is not tight in the slots. In other words, it is simply a driving key for transmitting motion through the body 1 to the spool. By reason of the reduced neck 7 an annular shoulder 12 is formed at the inner 45 end of the neck, and against this shoulder the inner end of the spool 8 seats. I prefer to form this end of the spool with a counterbore 13 of the same diameter as the body 1 adjacent the shoulder 12. In other words, the shoulder is 50 countersunk into the end of the spool.

In order to retain the spool and at the same time to enable it to be readily removable when desired, and also reversible, I provide the outer end of the spool with a counterbore 14, which is 55

preferably of the same diameter and depth as the counterbore 13. And I provide a follower 15, which may be in the form of a ring, but is illustrated in the form of a plate 15, which fits into the counterbore 14. Suitable means is provided for securing this follower to the end of the body 1, and this preferably consists of a plurality of circumferentially disposed fasteners, such as machine screws 16, which are threaded in openings spaced circumferentially around the wall of the body. With this arrangement it will be evident that the shoulder 12 and the edge of the follower 15, will resist any end thrust on the spool incidental to winding on or taking off a line from the spool. In time, the heads 9 become considerably worn, and eventually must be built up when they become too worn to function properly; or else a new cathead spool must be substituted. When the spool becomes worn it can be readily removed by removing the follower 15, slipping the spool off, and replacing it in a reversed position. When this is done, of course, the counterbore 14 fits over the shoulder 12, and the follower 15 fits into the counterbore 13. The spool 8 is preferably made of hardened steel, to enable it to resist wear. And as the shell of the spool is quite thin, the amount of metal in it is quite small. A relatively long-lived cathead results, which is of very slightly more cost to construct than an ordinary cathead.

One of the advantages of my construction is that I avoid any large projecting part on the end of the cathead spool. Such a projecting part is very objectionable because there is danger of a line becoming fouled by it. Accidents could happen from this cause.

By reason of the fact that the member that retains the spool 8 is not threaded so that it will screw onto the end of the neck 1, my construction has the advantage that the turning of the spool in either direction cannot loosen the 5 cathead. Furthermore by providing a great number of relatively small fastening devices disposed circumferentially, very small fastening devices or bolts can be employed which do not present any substantial obstruction on the outer face of the 10 follower 15 even if they are not countersunk. This results in a very serviceable construction which can be very economically built.

What I claim is:

In a cathead construction for draw-works or 15 the like, the combination of a shaft, a cathead having a hub rigidly secured to the shaft and having an enlarged tubular body projecting beyond the end of the shaft, said body having a neck of reduced diameter toward its outer end 20 and having an annular shoulder adjacent its inner end, a cathead spool received on the said neck, having a counterbore on its inner end receiving the said shoulder, a loose straight key-and-slot connection between the neck and the 25 spool permitting the spool to be readily removed for repair, the outer end of said spool having a counterbore of the same diameter as the first-named counterbore, a follower plate set into the end of said cathead spool and received in said 30 last-named counterbore, with its outer face flush with the end of the spool, said counterbores co-operating to enable the spool to be removed and applied against the said shoulder in a reversed position.

DANIEL L. BUTLER.
